UNITED STATES PATENT OFFICE

2,498,511

PAINTBRUSH CLAMP OR HOLDER

Nels J. Smith, Columbia Falls, Mont.

Application March 7, 1946, Serial No. 652,688

4 Claims. (Cl. 211—65)

1

My invention relates to paint brush clamps or holders and is particularly adapted for use in holding one or more paint brushes in paint cans or other containers containing paint or paint solvents, in order that the same will not dry out while not being used.

An important object of my invention is the provision of a device of the class described which can be used on cans or containers varying greatly in height.

Another object of my invention is the provision of such a structure which may be used on paint cans or containers of any given circumference or shape.

Another object of my invention is the provision of a novel, inexpensive clamping device for holding the paint brush handles.

Another important object of my invention is the provision of means for vertically adjusting the paint brush clamps in order that the brushes may be lowered into the fluid at any desired level.

Another object of my invention is the provision of a device in which a plurality of paint brush clamps can be mounted on a common vertical axis for rotation on a horizontal plane over the fluid within the container.

Another object of my invention is the provision of such a structure which is rigid and durable but which can be manufactured at a minimum cost.

The above and other objects of my invention will become apparent from the following detailed specification, attached drawings and appended claims.

Referring to the drawings wherein like characters indicate like parts throughout the several views:

Fig. 1 is a side elevational view of my novel construction mounted on a paint can or container;

Fig. 2 is a fragmentary view partly in vertical axial section and partly in side elevation;

Fig. 3 is a top elevational view similar to Fig. 1;

Fig. 4 is a fragmentary view of my novel paint brush clamp; and

Fig. 5 is a fragmentary sectional view taken on the line 5—5 of Fig. 2.

Referring with greater particularity to the drawings, the letter A designates an open-topped paint can or other container over which a pair of laterally spaced anchoring hooks 1 are placed. The extreme outer ends of hooks 1 may be joined by a connecting member 2 as illustrated in Fig. 5, if desired. For the purpose of increasing the frictional bite of the hooks 1 upon the inner surface

5 of the container A, I provide double teeth on the outer end of hooks 1 identified by the numerals 3 and 4. The inner ends of hooks 1 are formed or bent into vertically extending elongated tubular guides in the form of coils 5. The extreme inner ends of hooks 1, as shown particularly in Figs. 1 and 5, extend into and are held fast by the rolled edges of a retaining clip 6, which member 6 is positioned intermediate the coils 5. A stud 7, having a knurled head 8, is shown as having screw threaded engagement with clip 6. It will be obvious that by screwing stud 7 inwardly so that its extreme inner end makes contact with the outside surface of the pail or container A, that clamping hooks 1 may be frictionally locked in position, free from horizontal or vertical movements.

20 A pair of supporting rods or legs 9 extend vertically through a pair of laterally spaced tubular guides 5. Their upper ends are bent horizontally at 10 to project the open upper end of container A and terminate in a pivot pin-receiving loop or eyelet 11. The extreme lower ends of legs 9 are inwardly offset at 12 to prevent legs 9 from being accidentally withdrawn through guide members 5.

25 A vertically extending pivot pin 13 is carried by eye 11, and is held securely in place by a nut 14. A plurality of paint brush clamps or holders, identified in their entirety by numeral 15, are pivoted to pivot pin 13 for horizontal movements over the contents of the container A and are vertically separated from each other by spacers or the like 16.

30 Referring with greater particularity to my novel paint brush clamps, it will be seen, particularly by reference to Figs. 3 and 4, that they are constructed from a single piece of spring wire or the like and are so formed as to make a pair of spring arms 17 and 18, respectively, which are crossed at their intermediate portions, as indicated at 19, and which are connected at their inner ends by an anchoring portion in the form of a pivot pin-receiving loop or eye 20, through 35 which pivot pin 13 is adapted to pass. It will be noted that arm 17 has an outwardly closed longitudinally extending slot 21 adjacent its free end. As shown, slot 21 is formed by bending backwardly upon itself, the free end of spring arm 17. Through slot 21 the free end of arm 18 extends. It will be observed that free ends of arms 17 and 18 provide, outwardly of their crossed intermediate portions, an outwardly opening brush-receiving mouth and exert a yielding tension tending to close the mouth. It will also be

observed that the free end of arm 18 is longer than the free end of arm 17 whereby to provide a stop when cooperating with the closed end of slot 21 carried by the free end of arm 17.

Paint brushes, identified by the letter B, are shown in Figs. 1 and 2 as being securely held in the clamps 15.

It will be observed that the load carried by supporting rods 9 is considerably off-center with respect to the axis thereof. Hence, supporting rods 9 are adjustably, but frictionally, held in tubular guides 5 against accidental movement. However, support-rods 9 may be very readily manually adjusted when desired to compensate for varying levels of the fluid in container A into which it is desired to subject the bristle end of the brush B.

What I claim is:

1. In a device of the class described, a pair of laterally spaced anchoring hooks adapted to fit over the top edge of an open container, laterally spaced, vertically extending guide members on the outer ends of said hooks, means for maintaining the outer ends of said hooks in spaced relation to the walls of said container, a pair of supporting rods frictionally, adjustably mounted in said guide members, the upper ends of said supporting rods terminating in a supporting bracket, and a horizontally disposed paint brush holder pivoted on vertical axis to said supporting bracket for movements over contents of said container.

2. In a device of the class described, a pair of laterally spaced anchoring hooks adapted to fit over the top edge of an open container, laterally spaced, vertically extending tubular guide members on the outer ends of said hooks, adjustable means for maintaining the outer ends of said hooks in spaced relation to the walls of said container, a pair of supporting rods frictionally adjustably mounted in said tubular guide members, the upper ends of said supporting rods being bent into a horizontal position and terminating in a pin-receiving loop, a vertically disposed pivot pin in said loop and a plurality of horizontally disposed, vertically spaced paint

brush clamps pivoted to said pivot pin for movements over the contents of said container.

3. The structure defined in claim 2 in which each of said paint brush clamps comprises a pair of spring arms crossed at their intermediate portions and connected at their inner ends by an anchoring portion in the form of a loop, one of said arms having a longitudinally extending outwardly closed slot adjacent its free end through which the other of said arms is extended, said spring arms providing, outwardly of their crossed intermediate portions, an outwardly opening brush handle receiving mouth, and exerting a yielding tension to close said mouth.

4. In a device of the class described, an anchoring hook adapted to fit over the top edge of an open container, a vertically extending guide member on the outer end of said hook in which said guide member is formed by bending the outer end of said anchoring hook into a coil, a supporting rod frictionally adjustably mounted in said guide member, the upper end of said supporting rod terminating in a horizontally disposed supporting bracket, and a horizontally disposed paint brush clamp pivoted on a vertical axis to said supporting bracket for movement over the contents of said container.

NELS J. SMITH.
